(57) **CLAIM**

The ornamental design for an outdoor RV traction robot, as shown and described.

DESCRIPTION

FIG. 1 is a top, front, and left side perspective view of an outdoor RV traction robot showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the figures are for the purpose of illustrating the outdoor RV traction robot that form no part of the claimed design.

1 Claim, 5 Drawing Sheets
